United States Patent Office.

WASHINGTON J. CORTHELL AND PHILLIP RICHARDS, OF BOSTON, MASSACHUSETTS.

Letters Patent No. 70,699, dated November 12, 1867.

IMPROVED DOOR AND WINDOW-FASTENER.

The Schedule referred to in these Letters Patent and making part of the same.

TO WHOM IT MAY CONCERN:

Be it known that we, WASHINGTON J. CORTHELL and PHILLIP RICHARDS, both of Boston, in the State of Massachusetts, have invented an Improved Door and Window-Fastener; and we do hereby declare that the following is a full and exact description thereof, reference being had to the accompanying drawings, and to the letters of reference marked thereon, making a part of this specification, of which—

Figure 1 is a top view of the invention.

Figure 2 is a longitudinal section of the same.

Figure 3 is an end view of the same.

Figure 4 is a transverse section of the same.

The letter *a* represents the case or chamber, *b* the bolt, *c* its notch or recess, *d* the knob, *e* the shank of the knob, *f* a projection or stop on the knob; *g*, slots in the top of the bolt-case, *h* the spring below the bolt, and *i* the sunken space for the spring to drop into.

Our invention provides a cheap and safe lock or bolt for doors of all kinds, and also a secure fastening for windows; and in order that others may understand the nature and use of our invention, we will proceed to explain the same.

Fig. 2, in the accompanying drawings, clearly represents the different parts of the fastener, and fig. 1 represents the same as in use with the door or window-foot. It is made of any suitable metal. In fig. 1 is seen the outside part of the fastener, with its arms extended, and screw-holes in the arms to fasten it upon the wood. This covers a box or case, *a*, seen in figs. 2, 3, and 4, and it is designed to sink this box into the wood. Figs. 1 and 2 exhibit the slot *g*, made so that the knob *d* and its shank *e* may be moved back and forth at pleasure. By examining further fig. 2, the different parts of the fastener may be clearly explained. The said knob, with its shank, presses down upon one end of the spring *h*, and beneath this spring, and under the end of the shank, is a space marked *i*, giving room for the pressure downwards. On one side of the shank is seen a projection or stop, *f*. The bolt *b* has a notch or recess, *c*, in the bolt-chamber, the use of which will be explained. Suppose the door unbolted: shove forward the bolt by the knob, and turn the knob half way round, so that the projection *f* shall rest on the side of the slot. It will then be impossible to unbolt the door, and even turning the projection round to its former place, the bolt cannot be pushed back without pressing the knob on the side next the bolt downwards, so that the projection presses into the narrowest slot. The reason why the bolt cannot be pushed back is, because the spring *h* springs up into the recess *c*, and of course it cannot be pushed backwards without turning and pressing the knob in the right direction.

No burglar could push back the bolt from without, and, unless taught, no one could easily manage it. It will be very convenient to fasten pantry-doors and other doors against the curiosity of children. It will be an excellent window-fastener, for the bolt could not be slipped back by an inexperienced hand, though a pane of glass should be removed. The fastener is simple and easy of construction.

What we claim as our invention, and desire to secure by Letters Patent, is—

The combination and arrangement of the knob and shank *d* and *e*, the projection *f*, and the spring *h*, with the bolt *b*, constructed with its recess *c* moving back and forth in the case *a*, substantially in the manner and for the purpose above set forth.

WASHINGTON J. CORTHELL,
PHILLIP RICHARDS.
